UNITED STATES PATENT OFFICE.

ERNST MAHLER, OF NEENAH, WISCONSIN, ASSIGNOR TO KIMBERLY CLARK COMPANY,
OF NEENAH, WISCONSIN, A CORPORATION OF WISCONSIN.

APPARATUS FOR MAKING ORNAMENTAL PAPER.

1,329,130.

Specification of Letters Patent. Patented Jan. 27, 1920.

Application filed September 7, 1917. Serial No. 190,128.

To all whom it may concern:

Be it known that I, ERNST MAHLER, a citizen of Austria, (who has declared his intention to become a citizen of the United States,) residing at Neenah, in the county of Winnebago and State of Wisconsin, have invented certain new and useful Improvements in Apparatus for Making Ornamental Paper, of which the following is a specification.

My invention relates to improvements in ornamental paper and apparatus for making same, and it is of particular value as applied to the making of finished paper directly, without the necessity of printing or otherwise treating the paper after it leaves the paper-making machinery. A separate application has been filed by applicant on the "ornamental paper and process for making same", and bears filing date of December 21, 1917, and Serial No. 208,294.

The salient objects of the invention are to produce an improved ornamental paper having color applied thereto in such manner as to produce an ornamental finish having distinctive high light and shadow markings; to produce a paper of the class described in which the high lights may be of one color and the shadow effects in another color; to provide improved apparatus for producing the said classes of ornamental paper; to provide an apparatus of the class described which may be utilized in connection with ordinary paper-making machinery without the necessity of extensive re-designing or reconstruction of such machinery; to provide an apparatus of the class described which will result in the production of a paper having mechanical characteristics comparable with those possessed by ordinary uncolored paper; to provide an apparatus which is capable of continuous operation; to provide an apparatus which shall be capable of rapidly, economically, and efficiently imparting to the paper surface the desired ornamental appearance; and, in general, to provide an improved paper and apparatus for producing same of the character referred to.

As an example of one method of practising my invention, I utilize an ordinary paper-making machine having the usual Four-

drinier wire and associated apparatus. Preferably, the mechanism which imparts the customary lateral shake or vibratory movement to the Fourdrinier wire is thrown out of commission so that the motion of the belt is a simple straight line traveling movement. The elimination of the side shake results in imparting to the top of the paper a roughened surface, which roughened surface is of considerable advantage in carrying out my invention. After the paper in its travel with the Fourdrinier wire is sufficiently set or formed, I direct upon its upper surface a series of air-brush sprays of liquid color, the effect of which is to embed the color in the projecting roughnesses of the paper and thereby produce the desired ornamental finish.

In the drawings, which illustrate one form of paper machine upon which my improved paper is produced—

Figure 1 is a vertical section through the center of the machine;

Fig. 2 is a plan view of the machine shown in Fig. 1;

Fig. 3 is an elevation of a portion of the spray apparatus;

Fig. 4 is a section taken on the line 4—4 of Fig. 3;

Fig. 5 is a section taken on the line 5—5 of Fig. 3;

Fig. 6 is a section taken on the line 6—6 of Fig. 3;

Fig. 7 is a section taken on the line 7—7 of Fig. 3;

Fig. 8 is a vertical section through the spray nozzle;

Fig. 9 is an underside view of the spray nozzle;

Fig. 10 is an underside view of a modified form of color nozzle; and

Fig. 11 is an underside view of another modified form of color nozzle.

Describing the apparatus, and referring particularly to Figs. 1 and 2, it will be observed that the machine as a whole is mounted upon the usual cast iron side frames 20 and 21 suitably secured together. The Fourdrinier wire belt 22 is driven in the usual manner and is stretched over a series of rollers 23, 24, 25, 26, and 27. The deckle strap 28 fulfills its usual function of pre-

venting spreading of the pulp which is fed onto the Fourdrinier wire over the table or distributing box 29 adjacent the rear pulley 23. The suction boxes 30, 31, and 32 are of usual construction, which also applies to the couch roll 33, while the rolls and associated apparatus for finishing the formed web 34 are of customary design and operate upon the paper in the ordinary manner; they therefore need not be shown or described further. The usual mechanism for imparting side shake to the Fourdrinier wire is not shown in the drawings for the reason that such mechanism is dismantled or thrown out of operation when practising my invention.

On a set of standards 35 and 36 is secured an iron frame work 37 which extends over the machine from side to side. On the said frame work 37 is preferably secured a wooden platform or runway 38 for the convenience of the operator in making the various adjustments to the spray apparatus. The ends of said frame work 37 preferably comprise a pair of longitudinal members 39 and 40 (see Fig. 2) which are slotted, as shown at 41, 42, 43, and 44, in order to slidably receive the clamping bolts 45 of a pair of pedestal bases 46 and 47. The said pedestal bases 46 and 47 constitute base mountings for the vertical column rods 48 and 49 which carry the spray apparatus.

On each of the columns 48 and 49 is a pair of clamp mountings 50 (see Fig. 3). Said clamp mountings each comprises a split clamp portion having a pair of clamping screws 51 for securing the clamp 50 to the vertical column 48, and it is also provided with an offset horizontal column portion 52 apertured to receive one of the horizontal supporting tubes 53. The horizontal column portion 52 is split to clamp around the horizontal tube 53 when the clamping screws 54 (see Fig. 2) are screwed up.

By reason of the slots 41, 42, 43, and 44, the columns 48 and 49 may be clamped in such position as to bring the rods 53 in any desired inclined position with reference to the travel of the paper web. Also, by means of the double clamps 50, the said rods may be slid up and down the said columns 48 and 49. Also, the spacing of the said columns 48 and 49 may be readily changed if desired.

The top rod or supporting tube 53 constitutes the support for the color-distributing main 55 and the air-distributing main 56, said mains lying on either side of the upper tube 53 and being secured thereto by clamps 57 (see Figs. 3 and 6). Said clamps 57 are preferably split, as shown at 58, in order to permit adjustment of the said parts 57 along the tube 53, tightening being effected by the wing screw 59. The said

clamps 57 have small integral laterally-projecting lugs 60 and 61 drilled out to receive the mains 55 and 56.

The pipe 55 communicates with a supply of dye stuffs, for instance, a liquid anilin dye, which is stored in a suitable tank maintained at a constant pressure. The pipe 56 leads from a storage tank in which a supply of air is maintained at a substantially constant pressure. The said mains 55 and 56 are fitted with T connections, as at 62 and 63, a pair of connections, for instance as shown in Fig. 3, being adapted to feed a pair of flexible hoses 64 and 65 which fit over the suitably shaped ends of short branch pipes 66 and 67. The lower ends of said hoses 64 and 65 fit over the suitably shaped ends of the branch pipes 68 and 69, said pipes communicating with a color-control valve 70 and an air-cock 71.

The control valve 70 and the air-cock 71 are screwed onto the ends of the pipes 72 and 73, and by means of unions 74 and 75 are connected to short pipe sections 76 and 77. The air pipe 77 at its lower end screws into the air nozzle casting 79 which, as shown, has an integral arm 80 having a boss 81 for receiving the vertical color pipe 76. The boss 81 is split in order to constitute a clamp which may be tightened by means of the wing screw 82 to secure the pipe 76 firmly in position in said arm.

The upper portions of the color pipe 72 and air-pipe 73 are, in the present instance, mounted and secured in a special form of universal clamp designated as a whole 83, so organized as to allow of adjustment of the nozzle to deliver the jet of color spray in any desired direction with reference to the travel and surface of the moving paper web. Said clamp 83 comprises a sleeve clamp 84 bored out to receive the lower tube 53, and split, as shown at 85 in Fig. 5, accommodating a pair of clamping screws 86, whereby the said clamp may be moved as a whole along the lower pipe 53, or revolved around the axis of the said pipe 53. The said sleeve 84 is also provided with a lower central boss 87, suitably bored out to receive the mating portion of the swivel boss 88 constituting one end of the casting 89. The casting 89 may be clamped in any angular position with reference to the boss 87 by means of the clamping screw 90. The other end of the casting 89 is bored out to fit the corresponding circular end 91 of the casting 92, whereby the member 92 may be rotated into any angular position with reference to the casting 89. Clamping of the said casting 92 in such position is effected by means of the cap screw 93. The pipes 72 and 73 are secured to the member 92 in any desired position by means of a resilient strap yoke 94 perforated to receive a central clamping screw 95, and having its

ends 96 and 97 suitably shaped to fit the curved surfaces of the said pipes 72 and 73.

If it be desired to incline one or both of the supporting tubes 53 to the horizontal, this may be effected by reason of the swivel joint 98 interposed between the clamps 50 and 52, clamping of said swivel joint 98 in any desired position being effected by means of a cap screw 99, access to which may be had through an aperture 100 in the side of said clamp 52.

Describing the details of the spray nozzle, and referring to Figs. 3, 8, and 9, it will be observed that the lower end of the color-pipe section 76 is fitted with a cap 101 perforated with a slot 102. The air-pipe section 77 screws into the casting 79 and communicates with a horizontal bore 103 formed in said casting and into which is inserted a horizontal jet tube 104 having its open outer end flattened, as shown at 105, in order to provide a thin horizontal slot-like jet 106 immediately beneath the color slot 102. The tube 104 is secured in the open outer end of the bore 103 by means of a cap 107 having a tapered threaded aperture arranged to screw over a correspondingly tapered and threaded nose 108 on the casting 80. Said nose 108 is preferably slotted at three equidistant points, so that it will collapse slightly and grip the tube 104 when the threaded cap 107 is screwed home.

The operation of the apparatus is practically self-evident, in view of the drawings and the above description. A supply of uncolored pulp flows onto the upper surface of the Fourdrinier wire web and deposits thereon, forming a web of paper which, during its movement with the Fourdrinier wire, is gradually freed from water which is drained through the wire by gravity and by the suction due to the said wire passing over the suction boxes 30, 31, and 32. By reason of the fact that the usual side shake is not present, the pulp, however, does not deposit into uniform flat pulp, but has a rough upper surface having miniature peaks and valleys instead of being uniformly flat, as is the case when the side shake is present.

The spray apparatus, as shown best in Figs. 1 and 2, is preferably adjusted in such position that each jet of spray 109 strikes the surface of the paper at as flat an angle as possible, thereby causing the particles of color to strike only the tops of the peaks or roughnesses on the surface of the newly formed paper web. In the event that the paper is of considerable width, it may be found desirable to use more than a single spray. For instance, in Fig. 2, I have shown a set of three sprays 109, 110, and 111 which overlap and merge into each other, thereby covering the entire area of the traveling web.

While the color is being sprayed onto the

surface of the moving paper web, the latter is of course in a damp and uncompacted condition; but when the web has passed under the couch roll and traveled through the finishing or calendering rolls, the web may be thereby flattened or compacted to produce a paper having a uniform smooth and level surface and of the desired texture. Such finished paper, however, will be found to possess the same characteristics with reference to color and general appearance as were imparted thereto by the color-spraying apparatus.

The samples accompanying this application illustrate in a general way the characteristic appearance of single-color and duplex-color finished paper manufactured according to my invention.

If desired, I may with my improved process and apparatus produce two-color paper. If such is desired, I arrange the sprays of the two different colors so that they cross the line of travel of the belt from opposite sides and in opposite directions, so that one side of the peaks in the paper web is coated with one color while the other side of the peaks is coated with a different color. Beautiful effects may be produced in this manner.

If desired, slightly different forms of jets may be used. For instance, in Figs. 10 and 11 I have disclosed other forms of caps 101^a and 101^b. In the caps 101^a I utilize a slot 112, but the lower end of the slot 112 does not communicate with the interior of the cap 101^a except through a series of three small circular apertures 113. The cap 101^b is the same as the cap 101^a, with the exception that the slot 112 is not present, the color simply issuing directly from a set of three apertures 113.

The described details of operation and construction are merely illustrative of the invention, the scope of which should be determined by reference to the appended claims.

I claim—

1. In a device of the class described, the combination of a traveling Fourdrinier wire to support a paper web while forming, and means for spraying color on the upper surface of said web while maintaining a straight line movement of said wire, free from lateral shake.

2. In apparatus of the class described, the combination of a Fourdrinier wire, means for moving the same in a straight line while the paper is being formed on said wire, a supply of liquid color, a supply of air under pressure, and a mixing nozzle communicating with said supplies of color and air for spraying the said color onto the upper surface of a wet plastic paper web moving with said wire, said spray being arranged to impinge upon the surface of said web at an acute angle to the horizontal.

3. In apparatus of the class described, the combination of a Fourdrinier wire, means for moving same in a straight line free from lateral shake while the paper is being formed on said wire, thereby causing formation of depressions and elevations in the paper web, a supply of liquid color under pressure, a supply of gaseous fluid under pressure, and

a mixing nozzle communicating with said supplies of color and fluid for spraying the 10 said color onto the upper surface of the wet plastic paper web moving with said wire, said spray being arranged to impinge upon the surface of said web at an acute angle to the horizontal.

ERNST MAHLER.
